PACKING STAND

Henry D. Carlton, Highlands City, Fla., assignor
to Food Machinery Corporation, San Jose,
Calif., a corporation of Delaware

Application January 23, 1941, Serial No. 375,626

10 Claims. (Cl. 226—58)

This invention relates to packing stands and is particularly adapted for packing fresh fruits, vegetables, and the like in shipping cases.

While this invention is adapted for packing many different farm commodities, it is especially useful in the packing of peppers and accordingly will be described as adapted to this use.

It is an object of this invention to provide a simple, novel, and inexpensive means to facilitate the manual packing of farm produce into shipping cases.

It is another object of this invention to provide a simple packing stand which will facilitate the rapid delivery of a commodity to be packed into the shipping container and the presentation to the packer of a constantly changing supply of this commodity from which he may select a choice group of individual entities of the produce for a display layer.

It is yet another object of the invention to provide such a packing stand by which such a packing operation may be carried out with a relatively high degree of efficiency without requiring the use of power.

The manner of accomplishing the foregoing objects, as well as further objects and advantages, will be made manifest when taken in connection with the following drawings, in which:

Fig. 1 is a perspective view of a preferred embodiment of my invention showing the reciprocating platform thereof in elevated position before a packing box has been placed thereon.

Fig. 2 is a cross-sectional view at a reduced scale of the packing stand shown in Fig. 1 and illustrating the position of the parts at the start of a packing operation with a box resting on the table.

Fig. 3 is a view similar to Fig. 2 showing how the latch which retains the box table in elevated position may be released.

Fig. 4 is a view similar to Fig. 3 illustrating the depression of the box supporting table, and the step in the packing operation which follows this.

Fig. 5 is an enlarged detail sectional view illustrating the cam hooks of the aforesaid packing stand.

Fig. 6 is a detail perspective view of the double platform latch of the invention.

Referring specifically to the drawings, the packing stand 10 illustrated therein includes a frame 11 having a base 12 upwardly from which angle iron uprights 13 extend, these uprights having vertical guides 14 provided thereon which form guideways 14a. Connecting the uprights 13

5 is an angle iron cross member 15 which is adapted to support the discharge end of a produce hopper 16. Supported centrally on the cross members 15 and extending rearwardly therefrom is a bracket 20 on which is journaled a pulley 21, the purpose of which will be made clear hereinafter.

Slidable vertically in the guideways 14a is a gate 22 which is preferably formed of sheet metal, the lower edge of which is bent outwardly to provide a platform 23. Side edge portions 24 of the gate 22 extend downwardly in the guideways 14a below the lower edge of the gate 22 and each is connected with the platform 23 by a framework 25. The angle between the gate 22 and platform 23 is strengthened by a bar 26 welded to the lower face of the platform 23 along its rear edge. Secured as by welding to this bar 26 and to the bottom of the platform 23 are cam hooks 30, these hooks having cam faces 31 and latch openings 32. (See Fig. 5.)

Supported on the base 12 is a cubical frame 35 having bearings 36 on which is pivotally mounted a shaft 37 having a foot pedal 38 with a latch actuating bar 39 rigidly supported thereon. Extending between the lower ends of the uprights 13 is a shaft 40 on which side bars 41 of a double platform latch 42 are pivotally mounted. The bars 41 are connected by an upper latch 43 and a lower latch 44, each of these latches constituting an angle iron the horizontal flange of each of which is adapted to extend into the notches 32 of the latch cam hooks 30 when the platform 22 is in one of its two operating positions as will be made clear hereinafter. The double latch 42 is yieldably held in forward position by a spring 50 connecting the lower latch bar 44 to the cubical frame 35.

40 Connected to the cross bar 26 and extending over the pulley 21 is a cable 51 from which a counter-balance weight 52 is suspended, the latter yieldably holding the platform 22 and gate 23 in an elevated position when these are not held downwardly during the operation of the packing stand 10. The latch bar 43 is slightly notched at 55 to accommodate the cable 51 during the operation of the invention.

Operation

45 The normal position of the packing stand 10, between packing operations, is shown in Fig. 1. Here the gate 22 is seen to be in upward position closing the mouth of the produce hopper 16 when the platform 23 is empty. The platform 23 and gate 22 are at this time locked in upper-

most position by entry of the latch bar 43 into the notches 32 as shown in Fig. 2. A box B is now lifted by the packer onto the platform 23 and pushed backward against the gate 22 as shown in Fig. 2.

The packer now depresses the pedal 38 which swings the bar 39 rearwardly against the upright bars 41 of the compound latch 42, thus swinging the latter rearwardly and removing the latch bar 43 from the notches 32. The gate 22 and platform 23 are now held upwardly only by the counterbalance weight 52 and the operator, by bearing downwardly with his own weight on the box B, is able to depress the gate 22 and platform 23 so as to remove the support of the gate 22 from the produce, such as a supply of bell peppers P, in the hopper. The peppers behind the gate 22 are thus free to gravitate over the upper edge of the gate 22 and the corresponding edge of the box B, and be deposited in the box as shown in Fig. 4.

After the latch bar 43 has been withdrawn from the notches 32 as shown in Fig. 3, by depression of the pedal 38 and the downward movement of the platform 23 has started, the operator relaxes his pressure on the pedal 38, permitting the spring 59 to pull the compound latch 42 forwardly again while he is depressing the table 23. As the platform 23 in this downward movement approaches the position in which it is shown in Fig. 4, the lower latch bar 44 is cammed rearwardly by engagement with the cam faces 31 of the cam hooks 39 and is then pulled into the notches 32 as shown in Fig. 4 when these arrive opposite this bar. The operator now has access to a portion of the peppers remaining in the hopper 16 from which to select the more choice of the peppers for forming an upper display layer in completing the pack in the box B.

When the packing of the box B has thus been completed, the operator removes the packed box from the platform 23 onto a conveyor disposed at the lower level of the platform 23 and as he does this depresses the pedal 38 which causes the counter-weight 52 to return the platform 23 and the gate 22 to their elevated positions in which they are shown in Fig. 1.

What I claim is:

1. In a packing stand, the combination of: a vertically reciprocable platform adapted to support a box; a produce hopper disposed adjacent a given edge of said box; a gate for said hopper disposed between said box and said produce when said box is resting on said platform; and unitary means for mounting and supporting said platform and gate in an elevated position and lowering said platform gate and box as a single entity to withdraw said gate from supporting relation with said produce and permit the latter to gravitate over said gate and an adjacent edge of said box and into said box.

2. In a packing stand, the combination of: a vertically reciprocable platform adapted to support a box; a produce hopper disposed adjacent a given edge of said box; a gate for said hopper disposed between said box and said produce when said box is resting on said platform; and unitary counter-balanced means for mounting and supporting said platform and gate in an elevated position and lowering said platform gate and box as a single entity to withdraw said gate from supporting relation with said produce and permit the latter to gravitate over said gate and an adjacent edge of said box and into said box.

3. In a packing stand, the combination of: a vertically reciprocable platform adapted to support a box; a produce hopper disposed adjacent a given edge of said box; a gate for said hopper mounted on said platform and disposed between said box and said produce when said box is resting on said platform; and manually operated latch means for supporting said platform and gate in an elevated position and facilitating the lowering of said platform gate and box to withdraw said gate from supporting relation with said produce and permit the latter to gravitate over said gate and an adjacent edge of said box and into said box.

4. In a packing stand, the combination of: a vertically reciprocable platform adapted to support a box; a produce hopper disposed adjacent a given edge of said box; a gate for said hopper mounted on said platform and disposed between said box and said produce when said box is resting on said platform; counter-balance means for continually acting on said platform to return the latter to its upward position; and latch means for holding said platform in its elevated position.

5. In a packing stand, the combination of: a vertically reciprocable platform adapted to support a box; a produce hopper disposed adjacent a given edge of said box; a gate for said hopper mounted on said platform and disposed between said box and said produce when said box is resting on said platform; counter-balance means for continually acting on said platform to return the latter to its upward position; latch means for holding said platform in its elevated position; and latch means for retaining said platform in its lowered position.

6. In a packing stand, the combination of: a vertically reciprocable platform adapted to support a box; a produce hopper disposed adjacent a given edge of said box; a gate for said hopper mounted on said platform and disposed between said box and said produce when said box is resting on said platform; counter-balance means for supporting said platform and gate in an elevated position and facilitating the lowering of said platform gate and box to withdraw said gate from supporting relation with said produce and permit the latter to gravitate over said gate and an adjacent edge of said box and into said box; and unitary, manually-operated means adapted to latch said platform in either its elevated or lowered position.

7. In a vegetable packing stand, the combination of: means forming a vertical slideway and adapted to be positioned opposite the mouth of a produce hopper; a gate for said mouth slidably disposed in said means; a platform mounted on said gate for supporting a packing box; and counter-balance means for holding said platform and gate in elevated position so that said gate closes said mouth, said counter-balance means being yieldable to permit said platform to be depressed and thus lower said gate and open said mouth.

8. In a vegetable packing stand, the combination of: means forming a vertical slideway and adapted to be positioned opposite the mouth of a produce hopper; a gate for said mouth slidably disposed in said means; a platform mounted on said gate for supporting a packing box; counter-balance means for holding said platform and gate in an elevated position so that said gate closes said mouth, said counter-balance means being yieldable to permit said platform to be de-

pressed and thus lower said gate and open said mouth; latch means for automatically latching said gate and platform in elevated position or in depressed position; and means manually releasing said latch means to permit vertical movement of said gate and platform.

9. In a vegetable packing stand, the combination of: means forming a vertical slideway and adapted to be positioned opposite the mouth of a produce hopper; a gate for said mouth slidably disposed in said means; a platform mounted on said gate for supporting a packing box; counter-balance means for holding said platform and gate in elevated position so that said gate closes said mouth, said counter-balance means being yieldable to permit said platform to be depressed and thus lower said gate and open said mouth; and means for latching said platform and gate in depressed position.

10. In a vegetable packing stand, the combination of: means forming a vertical slideway and adapted to be positioned opposite the mouth of a produce hopper; a gate for said mouth slidably disposed in said means; a platform mounted on said gate for supporting a packing box; counter-balance means for holding said platform and gate in elevated position so that said gate closes said mouth, said counter-balance means being yieldable to permit said platform to be depressed and thus lower said gate and open said mouth; means for latching said platform and gate in depressed position; and manual means for releasing said latch means to permit said platform and gate to return to elevated position.

HENRY D. CARLTON.
